UNITED STATES PATENT OFFICE

STEVE MCKLEBECK, OF FAIRBANK, PENNSYLVANIA

DESIGN FOR A TABLE

Application filed March 2, 1929. Serial No. 30,299. Term of patent 14 years.

To all whom it may concern:

Be it known that I, STEVE MCKLEBECK, a citizen of the United States, residing at Fairbank, in the county of Fayette and State of Pennsylvania, have invented a new, original, and ornamental Design for a Table, of which the following is a specification. Reference is had to the accompanying drawings which form a part of the specification, and in which—

Fig. 1 is a top plan view of a table, showing my design.

Fig. 2 is a side elevation, the lower ends of the legs being broken off.

Fig. 3 is a side elevation viewed at right angles to Fig. 2.

I claim:

The ornamental design for a table, as shown.

STEVE MCKLEBECK.
